RECEPTACLE

Edwin J. Hutchison, Barnesville, Ohio

Application April 13, 1936, Serial No. 74,191

1 Claim. (Cl. 229—23)

This invention relates to boxes primarily for cigars or may be successfully employed for other purposes, and has for the primary object the provision of a simple and inexpensive device of this character which will be durable and efficient and may be manufactured and sold at a low cost.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a transverse sectional view illustrating a box constructed in accordance with my invention.

Figure 2 is a longitudinal sectional view illustrating the same.

Figure 3 is a perspective view illustrating the outer section of the body of the box and showing the same partly collapsed or folded.

Figure 4 is a plan view showing the blank from which the inner section of the body of the box is constructed.

Referring in detail to the drawing, the numeral 11 indicates the body of the box and 12 the cover for the box. The body comprises inner and outer sections separable from each other and which may be readily folded or collapsed when disassembled. The inner section is made from a blank and the latter is clearly shown in Figure 4. The blank comprises the wall 13 and the flaps 14 integral therewith. The material of the blank is weakened on the dotted lines so that the flaps may swing relative to the wall 13. The outer section is made from a strip bent to form the angularly related portions 15. A covering 16 is glued or otherwise secured over the angularly

related portions and also is placed over the cover 12 thereby hinging the cover to the outer section of the box. The blank shown in Figure 4 when assembled to form the inner section is placed within the outer section and snugly fits the latter completing the body 11 of the box with the cover 12 hinged thereto. The inner and outer sections of the body 11 may be separated and assembled readily and when separated may be folded for shipment. The front and rear walls of the body 11 are of less height than the end walls so that when the cover 12 is in body-closing position it will lie flush with the upper edges of the end walls.

A box of the character described is simple in construction and easy and economical to manufacture and may be made of various shapes and from any material suitable for the purpose.

Having described the invention, I claim:

A box comprising a body including inner and outer sections separable from one another and each foldable, said inner section including a bottom wall providing a bottom for said body and side walls integral with the bottom wall and foldable relative thereto, said outer section including integrally connected side walls adapted to fit over the side walls of the inner section and cooperate therewith in forming end, front and rear walls to the body, said side walls of the outer section being foldable relative to each other, a cover hinged on one of the walls of the outer section to provide a closure for the body, and a covering placed over the cover and the outer section and secured to said cover and outer section to hinge the cover to the outer section and to retain the walls of the outer section assembled with the inner section removable from the outer section.

EDWIN J. HUTCHISON. 40
